Primary Examiner — Cynthia Underwood(74) *Attorney, Agent, or Firm* — Kilpatrick Townsend & Stockton LLP**CLAIM**

The ornamental design for a protective cover for a tablet computer, as shown and described.

DESCRIPTION

FIG. 1 is a perspective view of the protective cover for a tablet computer showing our new design in an open position without a tablet computer included therein;

FIG. 2 is a second perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof; and

FIG. 8 is a right side elevational view thereof.

FIG. 9 is a perspective view of the protective cover for a tablet computer showing our new design in an open position with a tablet computer included therein; and,

FIG. 10 is a second perspective view thereof.

The broken lines represent portions of the structure and environment that form no part of the claim.
